CLAIM

The ornamental design for a golf club head, as shown and described.

DESCRIPTION

FIG. 1 is a front perspective view of a golf club head; FIG. 2 is a rear perspective view of the golf club head of FIG. 1;

FIG. 3 is a front view of the golf club head of FIG. 1;

FIG. 4 is a rear view of the golf club head of FIG. 1;

FIG. 5 is a top view of the golf club head of FIG. 1;

FIG. 6 is a bottom view of the golf club head of FIG. 1;

FIG. 7 is a toe view of the golf club head of FIG. 1;

FIG. 8 is a heel view of the golf club head of FIG. 1;

FIG. 9 is a front perspective view of a second embodiment of the golf club head;

FIG. 10 is a rear perspective view of the golf club head of FIG. 9;

FIG. 11 is a front view of the golf club head of FIG. 9;

FIG. 12 is a rear view of the golf club head of FIG. 9;

FIG. 13 is a top view of the golf club head of FIG. 9;

FIG. 14 is a bottom view of the golf club head of FIG. 9;

FIG. 15 is a toe view of the golf club head of FIG. 9; and,

FIG. 16 is a heel view of the golf club head of FIG. 9.

The broken line showing is included for the purpose of illustrating unclaimed subject matter and forms no part of the claimed design.

1 Claim, 8 Drawing Sheets
